UNITED STATES PATENT OFFICE

THEODOR ZETTERLUND, OF MILWAUKEE, WISCONSIN, ASSIGNOR TO THE KERNER AUTOMATIC HOIST COMPANY, OF MILWAUKEE, WISCONSIN

HOISTING MECHANISM

Application filed March 25, 1929. Serial No. 349,656.

This invention relates to a hoisting mechanism.

Objects of this invention are to provide a novel form of hoisting mechanism in which a hoisting drum sheave or member is carried by a hoisting drum shaft and is driven from either one or the other of two reversely rotating members, either of which may be operatively connected in driving relation to the hoisting drum, and to provide a brake mechanism positively, operatively connected to the hoisting drum and applied whenever the driving members are both operatively disconnected from the hoisting drum so that there is no possible chance of the slipping of the load.

Further objects are to provide a hoisting mechanism in which two positive clutches are employed and associated with control mechanism in such a manner that only one clutch may be closed at a time, the control mechanism being so related to the brake mechanism as to release the brake whenever either clutch is closed.

Further objects are to provide a clutch control mechanism which has a quick motion for closing either clutch, so that there is no grinding of the clutch jaws, but in which the clutching is positively and quickly effected, whenever the mechanism is operated in a predetermined manner.

Further objects are to provide a construction in which there are independent rock shafts for controlling the clutches and in which a balancing mechanism is employed and connected with the brake, so that the application of the brake always occurs when the two clutches are out, and so that the brake is always released when either clutch is operated.

Further objects are to provide a compact, serviceable and novel type of hoisting mechanism in which the entire apparatus is portable and self-contained, and in which the construction is simple, rugged and substantially fool-proof.

An embodiment of the invention is shown in the accompanying drawings, in which:

Figure 1 is a side elevation of the apparatus with parts sectioned off.

Figure 2 is a plan view of the mechanism with the upper part of the control mechanism and its associated casing removed, and with parts in section.

Figure 3 is a sectional view on a line 3—3 of Figure 1.

Figure 4 is a sectional view through the control shaft and associated mechanism.

Figure 5 is a detail of a spring construction employed in the clutch rock shaft.

Figure 6 is a sectional detail showing a portion of the trip or release mechanism.

Figure 7 is a sectional detail showing the clutch rock shaft and associated parts.

Referring to the drawings, particularly Figure 3, it will be seen that a hoisting shaft 1 is suitably carried by bearings formed in a casing 2. This hoisting shaft rigidly carries a hoisting sheave 3 and a hoisting drum 4 at opposite ends. Obviously, either one or the other of the drums may be omitted, as desired, or both may be used without departing from the spirit of this invention.

The hoisting shaft is driven from a jack shaft 5 by means of a pinion 6, rigidly carried by the jack shaft and meshing with a relatively large gear 7, rigidly carried by the hoisting shaft 1. These two shafts are therefore permanently, operatively coupled by the gearing.

A pair of bevel pinions or gears 8 are loosely mounted upon the jack shaft 5 and are rotated in opposite directions by means of a bevel pinion or gear 9, rigidly carried by the drive shaft 10. The shafts are suitably mounted in roller bearings carried by a stationary portion of the casing, and also the bevel gears 8 are carried by roller bearings and supported from a stationary portion of the machine, as is apparent from Figure 3.

The jack shaft has loosely splined thereon a pair of slideable clutch members 11, which are operated by means of forked levers 12, rigidly carried by the rock shafts 13 for the clutches. These rock shafts project outwardly beyond the casing, as shown in Figures 2 and 7, and are provided with operating arms or levers 15. Preferably, the levers engage the rock shafts 13 of the

clutches at their squared portions, as indicated in Figure 2.

The jack shaft 5 is provided with a rigidly attached brake drum 16 (see Figure 3) which cooperates with a brake band 17. This brake band is prevented from turning by means of the U-shaped member 18 (see Figure 1). The U-shaped member loosely and slidably fits one of a plurality of supporting pins 19 projecting outwardly from the casing of the machine, as shown in Figures 1 and 3, and carrying at their outer ends a shielding ring 20, as shown in Figure 3. In order to prevent the brake band from excessive wear at any one portion due to its contacting with the rotating brake drum when the brake is open, a limit screw 21 is provided and carried by a bracket and controls the rearward or outward motion of the U-shaped member 18, thus causing the brake band to be entirely free from contact with the rotating brake drum at the time when the brake band is untensioned. The brake band may be tightened by means of any suitable mechanism, for instance, a rod 22 (see Figure 1) may extend through a pivoted block carried by a lever 23, one end of such lever being pivoted to the opposite end of the brake band from that carrying the rod 22. The rod may be threaded and may carry adjusting nuts to take up for wear, as desired.

The lever 23 carries at its outer or free end a rod or link 24, as shown in Figures 1 and 2. This link 24 extends to the free end of a lever 25, the other end of the lever 25 being pivotally mounted upon a stationary portion of the machine.

Preferably, at approximately the center of the lever 25, a second lever or equalizing lever 26 is pivotally mounted. This lever is provided with socket bearings at its ends which receive the ball-shaped outer ends of adjustable rods 27. These rods 27 are also provided with ball-shaped inner ends which fit within sockets formed in extensions 28 of the levers 15 for controlling the operation of the rock shafts 13 for the clutches.

From the description thus far given, it is apparent that when the levers 15 are in their clutch open positions, as shown in Figure 2, that the central pivot 29 for the lever 26 will be in its outermost position and consequently, the brake will be applied. If, however, either lever 15 rocks into clutch closing position, the extension 28 thereof will release its pressure upon the rod or link 27, and will correspondingly allow the lever 26 to rock inwardly at one end. This accordingly moves the lever 25 and thus releases the brake. As soon as the clutch is open, the brake is again applied, as described above, for then both clutches will be in their open positions.

65 No spring mechanism has been shown as

associated with the brake band and the related mechanism, but obviously, any suitable spring construction can be used for aiding in the releasing motion of the brake band; or the brake band may be made of resilient material and may tend to open itself or release itself and thus aid in the motion of the related parts. This latter is the form shown in the drawings.

Each of the clutch rock shafts 13, as shown in Figure 7, is spring urged towards clutch closing position by means of the spring 30. This spring may have one end secured to a rigid portion of the machine and may loosely surround the rock shaft 13, its other end being hooked in a slot 31, (see Figure 5) formed in an adjustable sleeve or shield 36. This shield 36, as shown in Figure 7, is preferably provided with a socket 37 adapted to receive a suitable tool for rotating the shield. After the required tension has been obtained, a set screw 38 is tightened and thus locks the sleeve 36 to the rock shaft 13.

The clutch operating levers 15 are spaced apart slightly, and carry at their free ends rollers 39, as shown in Figure 2, which cooperate with cams 40, the cams being preferably placed one behind the other and, of course, in line with the cam follower rollers 39. The shape of one of the cams is shown in full lines and the other cam in dotted lines in Figure 2. The shape of the two cams is identically the same except that they are reversed. Although two cam plates are shown, it is to be distinctly understood that they are rigidly connected with each other and may, if desired, be integral, as indicated in Figure 4. Thus, after the cams are rotated, the cut-out portion of one or the other cam is presented to the appropriate roller 39. The corresponding lever 15, however, is prevented from moving inwardly by means of a hardened bearing plate 41, carried by the lever which contacts with a corresponding hardened bearing plate 42, carried by one arm 43 of a bell-crank lever, see Figure 2.

The other arm 44 of such lever, projects inwardly between the two portions of the cam. It is adapted to be struck by a trip pin 45 carried by the cam. The construction of the quick motion mechanism is of course duplicated on the opposite side of the control cam, as shown in Figure 2.

In operation, it is clear that after the cam is rotated in one direction, one of the cut-outs is presented to the corresponding roller 39. The roller, however, is prevented from moving inwardly until the pin 45 hits the corresponding lever 44 and thus trips the catch which restrains the rocking motion of the lever 15. Thus, when the pin hits the catch of the trip mechanism, the lever 15 moves inwardly very quickly under the influ-

ence of the spring 30, as shown in Figure 7. This throws the corresponding clutch into engagement with its rotating gear 8, suitably inter-locking teeth being provided on the ro-

5 tating pinions and clutch members as shown in Figure 3. This quick motion mechanism is provided for closing one or the other of the clutches. Through the link mechanism previously described, it is apparent 10 that the brake is released whenever a clutch is closed.

When the clutch is again opened the latching mechanism is re-set by means of a spring. The spring for one of the latching devices 15 is indicated by the reference character 46 in Figure 6, and it will be seen that it is loosely coiled about the pivot pin 47, for the latching mechanism, and has one end secured to such pin and the other end se- 20 cured to the trip lever 44.

The pin 47 may be carried within a socket formed in a portion of the casing and retained in place by means of a set screw 48, as shown in Figure 6.

25 The means for operating the control cam consists of a controller shaft 49, which is carried by an upwardly extending auxiliary casing 50, bolted to the main portion of the machine by means of the bolts 51. This 30 controller shaft and auxiliary casing are sectioned off in Figure 2, but are shown in detail in Figure 4. The controller shaft is provided at its lower end with a disc 52, equipped with a pair of downwardly extending 35 lugs 53, which fit into openings in the cam 40, as shown in Figures 2 and 4. The upper end of the controller shaft 49 carries any suitable control mechanism, for instance, a pulley 54 to which control cables not 40 shown are attached. Preferably the wheel 54 engages a squared portion of the controller shaft, as shown in Figure 4.

The device is adapted for a temporary elevator construction such as employed during the erection of a building. If a two-car elevator system is employed, then the main cable is wrapped around the sheave 3. If, however, a single car elevator system is employed, the cable is wound around the drum 50 4.

In order to avoid needless repetition of terms, the expression "drum" will be used in the claims as indicating either the sheave or the drum.

55 In order to insure the maintenance of the cam in neutral position when the hoist is not in operation, a spring-pressed lever 55 is provided with rollers 56 which fit into corresponding notches 57 (see Figure 1) 60 formed in the two portions of the cam.

Thus, these spring-pressed rollers tend to maintain the cam in neutral position against accidental shifting.

It will be seen that a novel form of hoisting mechanism has been provided by this

invention, which is of relatively simple construction, which is free from delicate and easily broken parts, and which is easy to operate.

It will be seen further, that the device is 70 substantially fool-proof; the brake is always set when both clutches are open and is always released when either clutch is closed.

Although the invention has been described in considerable detail, such description is 75 intended as illustrative rather than limiting, as the invention may be variously embodied and as the scope of such invention is to be determined as claimed.

I claim:

1. A hoisting mechanism comprising a hoisting shaft, a drum carried by said hoisting shaft, a jack shaft geared to said hoisting shaft, a pair of revolute members, means for rotating said members in opposite directions, clutches for selectively connecting said members to said jack shaft, a brake drum carried by said jack shaft, a brake for said drum, and mechanism operatively connecting said brake and clutches for 90 releasing said brake when either clutch is closed and for applying said brake when both clutches are open, and cam means for selectively operating said clutches. 85

2. A hoisting mechanism comprising a hoisting shaft, a drum carried by said hoisting shaft, a jack shaft, a pinion rigidly carried by said jack shaft, a gear rigidly carried by said hoisting shaft and meshing with said pinion, a pair of revolute members, means for rotating said members in opposite directions, clutches for selectively connecting said members to said jack shaft, a brake drum carried by said jack shaft, a brake for said drum, and mechanism operatively connecting said brake and clutches for 100 releasing said brake when either clutch is closed and for applying said brake when both clutches are open, and quick motion, 105 cam controlled means for operating said clutches. 110

3. A hoisting mechanism comprising a hoisting shaft, a drum carried by said hoisting shaft, a jack shaft geared to said hoisting shaft, a brake for said jack shaft, a 115 movable member for controlling said brake, an equalizing lever pivoted intermediate its ends to said movable member, a pair of reversely rotating members, clutches for selectively coupling one or the other of said reversely rotating members to said jack shaft, levers for operating said clutches, and means connecting said levers to opposite ends of said equalizing lever. 120

4. A hoisting mechanism comprising a 125 hoisting shaft, a drum carried by said hoisting shaft, a jack shaft geared to said hoisting shaft, a brake for said jack shaft, a movable member for controlling said brake, an equalizing lever pivoted intermediate its 130

ends to said movable member, a pair of reversely rotating members, clutches for selectively coupling one or the other of said reversely rotating members to said jack shaft, levers for operating said clutches, means connecting said levers to opposite ends of said equalizing lever, and quick motion mechanism for controlling said clutches.

5. A hoisting mechanism comprising a hoisting shaft, a hoisting drum carried by said shaft, a jack shaft geared to said hoisting shaft, a brake drum carried by said jack shaft, a brake band surrounding said drum, a brake operating rod controlling said brake band, a pair of reversely rotating members, clutches for connecting either of said reversely rotating members to said jack shaft, a pair of levers for operating said clutches, a brake lever connected to said brake rod, and an equalizing lever pivoted intermediate its ends to said brake lever, the ends of said equalizing lever being connected to the levers for operating the clutches.

6. A hoisting mechanism comprising a hoisting shaft, a hoisting drum carried by said shaft, a jack shaft geared to said hoisting shaft, a brake drum carried by said jack shaft, a brake band surrounding said drum, a brake operating rod controlling said brake drum, a pair of reversely rotating members, clutches for connecting either of said reversely rotating members to said jack shaft, a pair of levers for operating said clutches, a brake lever connected to said brake rod, and an equalizing lever pivoted intermediate its ends to said brake lever, the ends of said equalizing lever being connected to the levers for operating the clutches by means of rods, said last mentioned rods and said brake rod being adjustable.

7. A hoisting device comprising a hoisting shaft provided with a drum, power means, a pair of revoluble members driven in reverse directions by said power means, clutches for selectively, operatively coupling said revoluble members to said hoisting shaft, a pair of levers for controlling the operation of said clutches, springs urging said levers towards clutch-closing position, a pair of spaced cam discs controlling the movement of the free ends of the clutch controlling levers and each having a cut-out to permit the inward motion of the respective lever when the cam discs are rotated to predetermined positions, a pair of spring-pressed trip levers projecting into the space between the cam discs, a pin carried by said cam discs for striking one or the other of said trip levers, said trip levers normally restraining the inward motion of the clutch controlling levers.

8. A hoisting device comprising a hoisting shaft provided with a drum, power means, a pair of revoluble members driven in reverse directions by said power means,

clutches for selectively, operatively coupling said revoluble members to said hoisting shaft, a pair of levers for controlling the operation of said clutches, springs urging said levers towards clutch-closing position, a pair of spaced cam discs controlling the movement of the free ends of the clutch controlling levers and each having a cut-out to permit the inward motion of the respective lever when the cam discs are rotated to predetermined positions, a pair of spring-pressed trip levers projecting into the space between the cam discs, a pin carried by said cam discs for striking one or the other of said trip levers, said trip levers normally restraining the inward motion of the clutch controlling levers, and a controller shaft removably attached to said cam discs.

In testimony that I claim the foregoing I have hereunto set my hand at Milwaukee, in the county of Milwaukee and State of Wisconsin,

THEODOR ZETTERLUND.
